UNITED STATES PATENT OFFICE.

JOHN DREFS, OF OMAHA, NEBRASKA.

DESIGN FOR A BADGE.

51,260.

Specification for Design.

Patented Sept. 11, 1917.

Application filed July 23, 1917. Serial No. 182,356. Term of patent 3½ years.

To all whom it may concern:

Be it known that I, JOHN DREFS, a citizen of the United States, residing at Omaha, in the county of Douglas and State of Nebraska, have invented a new, original, and ornamental Design for Badges, of which the following is a specification, reference being had to the accompanying drawing, forming part thereof.

Figure 1 is a front view, and Fig. 2 is an edge view of a badge illustrating my new design.

I claim:—

The ornamental design for a badge as shown.

JOHN DREFS.

Witnesses:

FRED. DICKMAN,
HERMAN SOMMER.
